UNITED STATES PATENT OFFICE.

JULIUS CHARLES PETERSON, OF SPOKANE, WASHINGTON.

SWEATBAND FOR HATS.

1,349,472.

Specification of Letters Patent. Patented Aug. 10, 1920.

Application filed July 15, 1919. Serial No. 310,949.

To all whom it may concern:

Be it known that I, JULIUS C. PETERSON, a citizen of the United States, and a resident of Spokane, in the county of Spokane, 5 and State of Washington, have invented a new and Improved Sweatband for Hats, of which the following is a full, clear, and exact description.

This invention relates to improvements in 10 sweat bands for hats, an object of the invention being to provide a sweat band which can be adjusted to fit any ordinary hat, which will allow a circulation of air around the head, which will be comfortable to the 15 wearer, and which can be removed and replaced as desired.

A further object is to provide a sweat band which will be of general truncated conical form conforming with the shape of 20 the head and not with the shape of the hat as is customary in devices of this character in general use.

Hats are ordinarily made so that the 25 opening is oval and symmetrical. The human head is seldom symmetrical, and its shape is ordinarily too irregular to be oval, having, as it has, many "bumps." Usually the back of the head is wider than the forehead, and this is accentuated by the fact 30 that hair usually grows on the back of the head and never grows on the forehead. In consequence the ordinary sweat band, fastened to the inside of the crown of the hat around its lower edge, comes into contact 35 with the head at only a few points. The ordinary sweat band is of the same perimeter (or nearly so) at both top and bottom, so that it is similar in shape to a short, somewhat flattened, cylinder. The shape of 40 the head being an irregular ovoid, results in only the lower edge of the ordinary sweat band coming into contact with the head at a few points. Consequently the points of contact of the head with the edge of the band 45 are subjected to relative high pressure, adjacent parts have slight pressure, while parts entirely out of contact have no pressure. Discomfort is caused at the points of high pressure, the hat does not set securely on 50 the head, and extraneous forces, as the wind, or the jars of walking or riding, are likely to displace it. If the points of high pressure come opposite the arteries and veins which carry the blood to and from the scalp, 55 the circulation of the blood is interfered with and the scalp and hair follicles do not

receive the proper amount of nourishment from the blood that they should have in order for the hair to be in a healthy condition. The health and vitality of the hair is decreased, and if the hat is worn much, baldness may result.

Poor supply of blood to the scalp is only one of the causes of baldness. Another cause of lack of vitality in the hair is lack 60 of fresh air, so that perspiration, whether sensible or insensible, is not quickly evaporated. If the hair remains damp with perspiration, the poisonous products in the perspiration destroy the vitality of the hair. 65 Hair that is not perfectly healthy and that is of low vitality, is more susceptible to attack by the diseases which are further causes of baldness, such as dandruff. If, then, the circulation of the blood to the scalp is interfered with less, and ventilation of the hair is provided for, the health and vitality of the hair will be improved and the danger of 70 premature baldness decreased.

Another object of my invention is to 75 overcome the defects of sweat bands in general use, and embody the advantages above referred to, as will more fully hereinafter appear.

With these and other objects in view the 80 invention consists in certain novel features of construction, and combinations and arrangements of parts, as will be more fully hereinafter described and pointed out in the 85 claims.

In the accompanying drawings—

Figure 1 is a bottom plan view illustrating my improved sweat band in a hat;

Fig. 2 is a view in longitudinal section 90 through the center of the hat;

Fig. 3 is a view in transverse section 95 through the center of the hat;

Fig. 4 is a perspective view of the sweat band removed;

Fig. 5 is a view in elevation of the adjusting buckle 4;

Fig. 6 is an edge view of the adjusting buckle 4;

Fig. 7 is a view in transverse section; and

Fig. 8 is a view in elevation illustrating 100 one of the socket members 14.

1 represents a hat and 2 my improved sweat band located within the hat and having its ends 3, 3, adjustably secured together by means of a buckle 4. The strap 110 forming the sweat band 2 is so cut or made that its upper edge is shorter than its lower

edge so that when the sweat band is formed, it will be of general truncated conical form so that its upper portion will be spaced from the crown of the hat and will fit the head of the wearer. Furthermore, the sweat band will be spaced from the hat principally at its front and rear portions so as to allow a free circulation of air inside of the hat and also prevent the forehead and back 10 of the head from binding action by the hat.

The adjusting buckle 4 is shown in detail in Figs. 5, 6 and 7 and comprises four longitudinal bars 5, 6, 7 and 8 spaced apart and connected at their ends by flanges 10 and 11 for engaging the edges of the sweat band and preventing possibility of movement of the buckle vertically after it has been adjusted. The intermediate bars 6 and 7 of the buckle are offset laterally, as shown 20 in Fig. 7, and are provided with teeth 9 which engage the ends 3 of the sweat band and prevent slipping after adjustment. Both ends of the sweat band are inserted between the bars 6 and 7 and then one end 25 is passed between the bars 6 and 5, while the other end is positioned between the bars 7 and 8, so that the ends will be held by the buckle flat against the outer face of the sweat band.

At the front and rear portions of the sweat band a plurality of straps 12 are provided. Some of these straps are secured at their upper ends to the sweat band and others are secured at their lower ends to 35 the sweat band, and all of said straps at their free ends are provided with stud members 13 of ordinary snap buttons which engage socket members 14 fixed to the hat. These straps 12 hold the sweat band and 40 hat against independent vertical movement, but permit a flexibility of the sweat band longitudinally and laterally so that the hat will not bind the head.

At the sides of the sweat band a series 45 of stud members 13 are provided which engage socket members 14 fixed to the hat and any member of these snap button constructions may be employed as desired.

By reference particularly to Fig. 8, it will 50 be noted that the socket members 14 have elongated slots or sockets 15 therein and these sockets are positioned horizontally within the hat so that in the event of shrinkage or adjustment, or for any other reason 55 the studs may not exactly center in the sockets, they can nevertheless be effectually connected.

While I have illustrated the sweat band 2 as having a turned-up edge 2', it is, of 60 course, to be understood that this is purely a matter of taste and can be dispensed with, if desired.

The sweat band can be removed, adjusted or cleaned, and replaced in the same or in any other hat so that if an owner has one 65 sweat band which fits his head, he can utilize the same in any number of hats.

The arrangement of straps at the front and rear of the sweat band cause the band to tightly grip the head when the front or 70 rear of the hat tends to blow upward by the wind thus preventing the annoyance of the hat blowing off the head of the wearer.

Various slight changes may be made in the general form and arrangement of parts 75 described without departing from the invention, and hence I do not limit myself to the precise details set forth but consider myself at liberty to make such changes and alterations as fairly fall within the spirit 80 and scope of the appended claims.

I claim:

1. A sweat band for hats, comprising a strip, and straps for attaching said band to a hat, said straps located at the front 85 and rear portions of the sweat band, certain of said straps secured to the lower portion of the sweat band and others of said straps secured to the upper portion of the sweat band.

2. The combination with a hat, of a sweat band in the hat, straps secured to the front and rear portions of the sweat band, certain of said straps secured to the lower portion of the sweat band, and others of said straps 95 secured to the upper portion of the sweat band, all of said straps having securing devices at their free ends for attachment to the hat.

3. The combination with a hat, of a sweat 100 band in the hat, straps secured to the front and rear portions of the sweat band, certain of said straps secured to the lower portion of the sweat band, and others of said straps secured to the upper portion of the 105 sweat band, all of said straps having securing devices at their free ends for attachment to the hat, said sweat band at its front and rear portions spaced from the hat and at its side portions located against the hat and 110 secured thereto.

4. The combination with a hat, a truncated conical sweat band in the hat, straps secured to the front and rear portions of the sweat band, certain of said straps secured to the lower portion of the sweat band, and others of said straps secured to the upper portion of the sweat band, all of said straps having securing devices at their free ends for attachment to the hat, and other securing devices connecting the side portions of the sweat band with the hat.

JULIUS CHARLES PETERSON.
